UNITED STATES PATENT OFFICE.

ALBERT J. HORTON, OF WHITE PLAINS, NEW YORK.

CIRCUIT-CONTROLLER.

1,347,859.

Specification of Letters Patent. Patented July 27, 1920.

Application filed July 15, 1915. Serial No. 40,122.

To all whom it may concern:

Be it known that I, ALBERT J. HORTON, a citizen of the United States, residing at White Plains, in the county of Westchester 5 and State of New York, have invented new and useful Improvements in Circuit-Controllers, of which the following is a full, clear, concise, and exact description, reference being had to the accompanying drawings, forming a part of this specification.

This invention relates to improvements in circuit controllers. More particularly it relates to controllers for sewing machine motors, although it will be apparent that controllers embodying the various features of the invention may be advantageously employed in other relations.

One of the objects of the invention is to provide a simple, compact and reliable controller embodying a combined abutting and sliding contact switch mechanism.

A further object is to provide a spring returned controller adapted to automatically interrupt circuit should the return spring break or become otherwise disabled.

A further object is to provide an inclosed controller having a removable cover with simplified means whereby removal of said cover disconnects the controller from circuit.

Numerous other objects and advantages of the invention will hereinafter appear.

The accompanying drawing illustrates one embodiment of the invention and the same will now be described, it being understood that the invention is susceptible of embodiment in various other forms falling within the scope of the appended claims.

In the drawings,

Fig. 1 is a perspective view of the controller;

Fig. 2 is a front elevation of the controller with the cover thereof removed;

Fig. 3 is a sectional view on line 3—3,

Fig. 2;

Fig. 4 is a rear elevation of the insulating base contained within the casing;

Fig. 5 is a sectional view on line 5—5, Fig. 2; and,

Fig. 6 is a diagrammatic view illustrating the use of the controller for governing an electric motor.

Briefly described the controller includes an insulating base 1 carrying a resistance 2 and stationary contacts 3, 4, 5, 6, 7, 8, a mov-

able contact 9 to coöperate with said stationary contacts, an inclosing casing 10 for the aforesaid parts, an external operating member 11 for the contact member 9 and a mechanical brake 12 for the controlled motor 60 fixed to said contact operating member 11. The casing 10 has a removable cover 13 provided with a plug 14 adapted for connection to the line wires and coöperating with terminal lugs 15 and 16 on the insulating 65 base 1.

More specifically considering the switch mechanism the movable contact 9 functions as an abutment contact to engage and bridge contacts 3 and 8 and as a sliding contact to 70 progressively engage and bridge contacts 4, 5, 6 and 7 with contact 8, the contacts 3 to 7 being connected to the resistance 2. The contact 9 comprises a bar swiveled at 20 to the end of an arm 21 fulcrumed on a pin 22 75 projecting laterally from a second arm 23 fixed to a shaft 24 extending transversely through the casing 10. The arm 21 has a lateral lug 25 to abut a shoulder 26 on the arm 23 and a spring 27 mounted on the 80 shaft 24 acts upon the arm 21 to normally effect abutment of said lug and shoulder. Thus the arm 21 is normally held in a fixed relation with respect to the arm 23 whereby rotation of the shaft 24 in a counter-clockwise direction will effect movement of contact 9 to make abutting engagement with the stationary contacts 3 and 8. On the other hand, after the contact 9 initially engages the stationary contacts the pivotal connection of arms 21 and 23 permits a play of said arms against the action of spring 27 to force the contact 9 slidingly over the remaining contacts upon continued rotation of shaft 24. The spring thus reacts upon the arm 95 21 and contact 9 to hold the latter firmly against the stationary contacts and upon reverse operation of the shaft 24 maintains the contact 9 in engagement with the stationary contacts until it swings clear of the 100 same by outward movement. Accordingly the mechanism functions as an abutment type switch to initially complete circuit and to finally interrupt circuit, and as a sliding type switch to vary the resistance. 105 In this connection it is to be noted that the spring 27 is so arranged as to function both for the purpose just described and also for return of the controller when released. One extremity 28 of this spring bears against a 110

screw 29 fixed within the casing while its opposite extremity 30 bears against a roller 31 carried by a bell crank extension 32 of the arm 21. Further, it is to be noted that 5 if the spring 27 should break or become otherwise disabled the arm 21 would be freed and that said arm is so disposed as to swing contact 9 clear of the stationary contacts under such conditions (see dotted lines, 10 Fig. 3). This insures against use of the controller in a disabled condition and in consequence constitutes an important and highly desirable protective feature.

The base 1 is preferably of porcelain and 15 is secured within the casing by screws 33, 34 and 35 threading into bosses on the rear wall of said casing. The base is so shaped as to give clearance for the contact carrying arm 21, to provide a channel 36 for the 20 resistance and, as shown in Fig. 3, to provide a bushing 37 for a conductor outlet in the rear of the casing. The resistance 2 is shown in the form of wire wound around the base in the channel 36 and provided 25 with an insulating covering, such as cement, to adhere to the base. The resistance has leads 38, 39, 40, 41 and 42 which are connected to the contacts 3, 4, 5, 6 and 7 respectively, it being understood that these 30 leads are connected to different points on the resistance. Each of the contacts 3 to 7 comprises a bolt passing through the base, the head of the same forming a binding post for the resistance lead at the rear of 35 the base and the nut thereof serving for its contact portion. The contact 8 comprises an oblong block secured to the base by screws 43 and 44, Fig. 4, while the aforesaid line terminals 15 and 16 comprise headed 40 studs projecting through the base from the rear thereof. The studs 15 and 16 are slideable in bearings 50 and are pressed forwardly in said bearings by springs 51 and 52. The spring 51, which bears against the 45 stud 16, is secured to the base by the securing screw 44 of the contact 8, whereby the spring provides for electrical connection between said stud and said contact. The spring 52 bearing against the stud 15 is se- 50 cured to the base by a bolt 53 forming a binding post, said stud 15 being electrically independent of the parts described. In addition to the aforesaid electrical parts the base also carries binding posts 54, 55 and 56 55 for the connections shown in Fig. 6.

Referring to Fig. 6, the same shows a compound motor M having an armature A, a series field F and a shunt field f. The motor, armature and series field are connected between binding posts 55 and 56, the former being connected to binding post 53 and thence to line terminal 15, while the latter is connected to contact 7. The shunt field of the motor, on the other hand, is connected between binding posts 55 and 54, the

latter being connected to contact 3. Thus, with the resistance connected to the contacts 3 to 7 and with the contact 8 connected to the terminal stud 16, as above set forth, it will be apparent that the bridging of contacts 3 and 8 will complete the motor circuit through all of the resistance 2, whereas movement of the contact 9 over the stationary contacts will gradually exclude the resistance from circuit. In this connection 75 it will be observed that there are three leads from the controller to the motor, namely those from binding posts 54, 55 and 56, and upon reference to Fig. 2 it will be noted that these leads are connected to the binding 80 posts on the front of the base and are taken out of the casing through the bushing 37 provided by the base.

The construction of the plug on the cover of the casing is best illustrated in Figs. 3 85 and 5. It includes an insulating block 60 secured to the casing by screws 61 and having terminal members 62 and 63 fixed in spaced recesses therein. At their outer ends the terminal members 62 and 63 are provided with binding screws 64 and 65 respectively while the inner ends of said members are recessed to receive the points of the terminal studs 15 and 16 carried by the base 1. The arrangement is obviously such that 90 the terminal members on the cover will register with and engage the terminal studs on the base when the cover is set in place and moreover will press the studs inwardly against the springs to insure firm engagement between the terminal parts. As will be understood the binding screws 64 and 65 are provided for connection to the supply wires and the insulating block 60 is provided with a flange 66 which, together with 100 an insulating plate 67 on the casing, forms a complete inclosure for the binding screws except for a notch 68 in the lower flange to provide an inlet for the line wires. The insulating plate 67 is secured in place by 105 screws 69 whereby it may be readily removed to give access to the binding screws for connection to the line wires.

The cover 13 of the casing is secured in place by hooks 70. These hooks, as illustrated in Fig. 3, have shanks slidably mounted in the ends of the casing and provided with springs 71 tending to retract the same in their sockets. The cover is provided with notches 72 to receive the shanks 120 of said hooks, said notches being adapted to register with said shanks and the locking of the cover being effected by turning the hooks to the positions indicated in Fig. 1. The notches are provided with side flanges 125 73 having cam edges 74 whereby the hooks are secured against accidental turning but yet may be turned where desired with only a comparatively slight resistance.

As illustrated, the controller is arranged 130

for suspension in a vertical position, being provided at its upper end with lugs or ears 75, 76 and 77 for attachment to the table of a sewing machine, while the operating member 11 for the switch mechanism comprises a lever fixed to the shaft 24 and adapted for connection to the sewing machine treadle.

The brake 12 comprises a holder carrying a brake shoe 78 of leather or other suitable material, said holder being fixed to a rod 79 adjustably secured as by a set screw 80 in a bearing 81 provided on the member 11. As will be understood, the brake is arranged to engage the pulley of the driving motor and is to be set and released upon movement of the controller to circuit making and breaking position. Thus the direct connection of the brake to the member 11 will insure the desired relative operations of the brake and controller and the particular connection between the brake and member 11 will permit adjustment of the former in all directions.

What I claim as new and desire to secure

25 by Letters Patent is:

1. In a circuit controller, the combination with stationary contacts and a contact member adapted to coöperate therewith, of means for operating said contact member in an abutting relation relative to certain of said contacts and in a sliding relation with respect to other of said contacts, said means including a return spring so associated with said member as to render engagement there- 35 of with said stationary contacts dependent upon said spring.

2. In a circuit controller, the combination with stationary contacts and a coöoperating movable contact, of means for operating the latter contact in an abutting relation with respect to certain of said fixed contacts and in a sliding relation with respect to other of said fixed contacts, while maintaining a tendency of said movable contact to become 40 and remain disengaged from said fixed contacts, said operating means including a return spring so associated with said movable contact as to render engagement of said fixed and movable contacts dependent upon 45 said spring.

3. In a circuit controller, the combination with stationary contacts and a movable contact adapted to coöperate therewith, of means for effecting operation of said movable contact both as an abutting and as a sliding contact with respect to said fixed contacts while at all times maintaining a tendency of the former against engagement with the latter, said means including a 55 spring for rendering the same effective to cause engagement of said contacts irrespective of such tendency and for imposing upon said movable contact a positive bias against such engagement.

65 4. In a circuit controller, the combination

with stationary contacts, of a coöperating contact, supporting means therefor providing an abutting and a sliding movement thereof relative to certain of said stationary contacts, an operating member and a single 70 spring normally biasing said movable contact out of engagement with said stationary contacts, engagement of said stationary contacts by said movable contact being dependent upon said spring.

5. In a circuit controller, the combination with stationary contacts, of a coöperating contact having means supporting the same for abutting movement with respect to certain of said stationary contacts and sliding 80 movement with respect to other of said stationary contacts, an operating member for said movable contact and a return spring for said movable contact so associated therewith as to tension the same against said stationary contacts when operated by said member and to render engagement of said movable contact with said stationary contacts dependent upon its action.

6. In a circuit controller, in combination, 85 a base, a plurality of contacts fixed to one side thereof, a movable contact, means supporting said movable contact to swing in a plane perpendicular to the plane of said fixed contacts and also to move in a plane 90 parallel thereto, said movable contact tending to swing away from the plane of said fixed contacts and a spring associated with said supporting means and said movable contact to both normally bias said movable contact away from said fixed contacts and press said movable contact against said fixed contacts throughout a given range of movement of the former.

7. In a circuit controller, in combination, 100 a base, a plurality of contacts fixed to one side thereof, a movable contact, means supporting said movable contact to swing in a plane perpendicular to the plane of said fixed contacts for causing abutting engagement therewith and also to move in a plane 105 parallel thereto for sliding engagement, said movable contact being pivotally supported by said means and tending to swing away from the plane of said fixed contacts, and a spring associated with said supporting means and said movable contact to both bias said movable contact relatively to said supporting means and toward said fixed contacts and bias said supporting means to disengage said movable contacts from said fixed contacts.

8. In a circuit controller, in combination, 115 a supporting base, a series of contacts fixed thereto, a pivoted arm movable in a plane 120 at right angles to the plane of said contacts, and a contact member fulcrumed to said arm to coöperate with certain contacts of said series in an abutting relation and with other of said contacts in a sliding relation,

said contact member having a tensioning spring and being disposed on said arm to move away from said series of contacts when relieved of the tension of said spring irrespective of the position of said arm.

9. In a circuit controller, in combination, a supporting base, a series of contacts mounted thereon, a pivoted arm movable in a plane at right angles to the plane of said contacts and a contact fulcrumed to said arm to coöperate with certain of said contacts in an abutting relation and with certain others in a sliding relation, said contact having a tensioning spring and being disposed on said arm to move away from the plane of said series of contacts when relieved of the tension of said spring and said spring serving also as a permanent biasing means for said arm.

10. In a circuit controller, the combination with stationary contacts, of a pivoted arm, a contact member fulcrumed to said arm to be thereby operable as an abutting and sliding contact with respect to said stationary contacts, and a single spring biasing said arm in one direction relative to said fixed contacts irrespective of the position of said arm, and biasing said contact in one direction with respect to said arm.

11. In a circuit controller, the combination with a series of stationary contacts, of a pivoted arm, a contact member pivoted to said arm to be thereby operable in an abutting and sliding relation with respect to said stationary contacts, said contact member in all positions of said arm tending to swing away from said stationary contacts and a return spring for said arm also acting upon said contact member when operated to tension the same against said stationary contacts.

12. In a circuit controller, in combination, an insulating base, switch contacts and terminal devices carried by said base, an inclosing casing for said base, the former having an opening for ready insertion of the latter, a switch contactor carried by said casing for coöperation with the contacts of said base, a removable closure member for the opening of said casing and line connected terminal devices carried by said closure member to engage the terminals of said base.

13. In a circuit controller, the combination with a switch mechanism, of an inclosing casing therefor having a removable cover

to give access to said mechanism, a terminal device carried by said removable cover for connection to the line wires and line terminals associated with said switch mechanism and structurally independent of the contacts thereof to engage said terminal device on the cover of said casing, said terminals being yieldable with respect to said device whereby removal of said cover from said casing serves to deenergize the appliances contained therein.

14. In a circuit controller, in combination, an inclosing casing having a removable front wall and a conductor opening in the rear wall thereof, a flat insulating base to be inserted within said casing from the front thereof and having a tubular portion adapted to fit within and extend through said conductor opening, resilient terminals carried by said base adjacent the front of said casing, and line connected terminal devices carried by said removable front wall in such relation as to engage said terminals of said base while said wall is secured in place and to disengage said terminals upon removal of said wall.

15. In a circuit controller, in combination, an inclosing casing, a flat insulating base secured therein, said base being divided vertically into resistance and contact carrying sections and provided at one end with an integral tubular portion projecting through a wall of said casing to provide a conductor passage, resistance and contacts fixed to their respective portions of said base, said resistance being connected to certain of said contacts and a movable contact supported within said casing to coöperate with said stationary contacts.

16. In a circuit controller, in combination, a casing, a contact supporting base fixed therein, contacts fixed to said base, a shaft revolubly supported in said casing, an arm fixed to said shaft, a coöperating contact for said fixed contacts pivotally suspended from said arm, said suspended contact tending to clear said fixed contacts in all positions of said arm and a spring surrounding said shaft with one end bearing against a fixed part and its other end bearing against said suspended contact member to bias said arm and to also bias said contact with respect to said arm.

In witness whereof, I have hereunto subscribed my name.

ALBERT J. HORTON.
